UNITED STATES PATENT OFFICE.

JOHN A. McGINNIS, OF WHEELING, WEST VIRGINIA, ASSIGNOR TO WHEELING STAMPING COMPANY, A CORPORATION OF WEST VIRGINIA.

FEEDER FOR METAL BLANKS.

Application filed June 27, 1921. Serial No. 480,658.

To all whom it may concern:

Be it known that I, JOHN A. McGINNIS, a citizen of the United States, residing at Wheeling, in the county of Ohio and State 5 of West Virginia, have invented a new and useful Improvement in Feeders for Metal Blanks, of which the following is a full, clear, and exact description, reference being had to the accompanying drawings, forming 10 a part of this specification, in which:

Figure 1 is a side elevation partly broken away of a feeder embodying my invention;

Figure 2 is a plan view;

Figure 3 is a section on the line III—III 15 of Figure 2;

Figure 4 is a vertical section taken in a plane at substantially right angles to the plane of the section of Figure 3;

Figure 5 is a top plan view with some of 20 the feeder members removed;

Figure 6 is a side view of one of the feeder members;

Figure 7 is a top plan view of the cut-off member;

25 Figure 8 is a plan view partly broken away, showing certain parts of the mechanism;

Figure 9 is a perspective view of one of the lever members, and

30 Figure 10 is a view partly in side elevation and partly in vertical section showing the cam post and adjacent parts.

My invention has relation to a feeder for 35 metal blanks and is particularly designed for use in feeding the blanks used in the manufacture of the bodies and caps of collapsible metal tubes, although it is equally well adapted for use in feeding other circular disks or blanks.

40 The object of my invention is to provide a simple, efficient and reliable feeder of this character by means of which the blanks may be fed successively and at regular intervals to the machines or dies which act upon the 45 blanks after they are fed, the delivery of the blanks by the feeder being in timed relation to the movement of the forming dies.

The nature of my invention will be best 50 understood by reference to the accompanying drawings in which I have shown a preferred embodiment of my invention, which will now be described, it being premised, however, that various changes may be made in the details of construction, arrangement 55 and combination of the several parts with-

out departing from the spirit and scope of the invention as defined in the appended claims.

In these drawings, the numeral 2 designates a suitable hopper which is rigidly secured to a base plate 3. This hopper preferably has downwardly curved convex inner walls serving to prevent piling up of the blanks being agitated. The shell of this hopper has its lower portion 2^a of larger 60 internal and external diameters than the intermediate portion of the hopper, this enlarged and offset portion of the hopper cavity forming a seat for an annular ratchet ring 4 having peripheral teeth 5. The ring 4 is designed to be given a step-by-step rotary movement in any suitable manner. In the construction shown, this movement is effected by means of the spring pressed pawl 6, which is pivotally mounted at 7 upon a 65 reciprocating pawl carrier bar 8. The bar 8 is mounted to reciprocate in suitable guides in the base plate 3 and has rigidly secured thereto an upwardly extending post 9 in which is formed an oblique cam slot 10 (see Figure 10). The slot is engaged by an anti-friction roller 11 on the end of an arm 12 which is connected to some moving part of the machine which the feeder supplies, such as the reciprocating cross head or die carrier 13. (See Figure 1). As the member 13 is reciprocated vertically, the parts thus described will operate to effect a step-by-step rotation of the ring 4.

Secured to the ring 4 to rotate therewith 90 within the lower portion of the hopper cavity are two superimposed feeder members 15 and 16. These may be connected to the ring 4 in any suitable manner as by the key 17 indicated in Figure 5. The two parts 95 are of annular form, and are provided on their peripheries aligned vertical feeding channels 18 through which the blanks may pass between said members, the lower portion of the hopper cavity and the inner wall 100 of the ring 4. The two members 15 and 16 are separated by a cut-off device 19 shown in Figures 3, 4 and 7, and which is rigidly keyed to a boss 3^a on the base plate 3, so as to remain stationary. This cut-off member 105 is in the form of an annular plate having a segmental projection 19^a. This projection 19^a occupies a position directly over the discharge opening 20, which leads through the base plate 3 and communicates with the 110

upper end of a delivery chute 21, the construction and arrangement of the passage 20 and the chute 21 being such that the metal blanks A can drop therethrough in edgewise position.

22 designates an agitating device within the hopper cavity and which is for the purpose of preventing the metal blanks from packing too solidly in the hopper. This device 10 vice is in the form of the frustum of a cone and is mounted to revolve upon the pin 23 which is secured in the base plate 3. Its periphery is formed with a helical rib 24, the pitch of which is directed upwardly to thereby exert a constant lifting action upon the blanks. The cone is rotated by a suitable connection with the feeder member 15, such as the dowel pin 25, shown in Figure 3.

26 designates a gate which is arranged to move into and out of the upper portion of the chute 21 so as to alternately support and release a blank falling through the chute. This gate is shown in blank-supporting position in Figure 4. The gate is periodically actuated in proper timed relation by any suitable means. In the drawings I have shown the gate as being carried by a reciprocating bar 27 which is actuated by a lever 28 fulcrumed to the base plate 3 at 29 and having its opposite end provided with a post 30 which projects upwardly between the two followers 31 of the centralizing springs 32, which are seated in the reciprocating pawl carrier 8. The lever 28 also has an upwardly projecting guide pin 33 which works in a guide slot 34, as best shown in Figure 2. It will be readily seen that the gate 26 will by means of the connections just described, be reciprocated in proper timed relation to the movements of the machine being supplied by the feeder, the actuating movement being derived from the part 13 of such machine.

If, for any reason, it is desired to empty the hopper quickly, the member 27 may be pulled outwardly to withdraw the gate 26 from the chute and may be held in this position by a latch device 35, which can be swung into engagement with a notch 36 in said member 27.

50 The operation will be readily understood from the foregoing. The metal blanks A to be fed are placed in mass in the cavity of the hopper 2 where they are constantly subjected to the loosening action of the agitator 22. 55 The blanks are gradually worked into edgewise position, passing down into the channels in the feed members 15 and 16, as shown in Figure 4, the lowermost blanks resting upon the upper surface of the base plate 3 60 until a lower blank is turned into registry with the upper end of the discharge passage 20. At this time all of the blanks immediately above the blank which is to be discharged into said channel are supported by 65 the segment 19^a of the separator or cut-off

device 19. Therefore, only one blank at a time can be discharged, such discharge occurring at each step-by-step rotation of the parts. Each blank is held in the shute 21 until it is released at the proper time by the withdrawal of the gate 26.

My invention provides a feeder of the character described which is simple in its construction and operation, there being a few movable parts and those being of a character such that they are not likely to get out of order. The action of the feeder is therefore reliable and efficient and can be depended upon to supply the blanks in regular succession and at the proper time intervals to the dies which shape the blanks. When the feeder is used in connection with machines for forming blanks for parts of collapsible tubes, the dies in question may be the extrusion dies which form the body of the tubes, or they may be the dies which shape the caps or closures for the tubes. As above stated, however, my invention is not limited to use in connection with machines of this particular character.

I claim:

1. In a feeder for metal blanks, a hopper having downwardly curved convex inner walls, a cone-shaped agitator rotatably mounted within the hopper and having a helical lifting rib upon its periphery, said rib having a pitch sufficient to move the blanks circumferentially simultaneously with the lifting thereof, and rotatable feeder means in said hopper below said agitator, substantially as described.

2. In a feeder for metal blanks, a stationary hopper having downwardly curved convex inner walls, an agitating device rotatably mounted within said hopper, said agitating device being of conical form with means upon its surface adapted to exert a progressive and gradual lifting action on the blanks in the hopper, and rotatable feeder means in said hopper below said agitator, substantially as described.

3. A blank feeder comprising a hopper, two superimposed feeder members rotatably mounted within the hopper and having peripheral feed channels, and a blank separator or cut-off device mounted in fixed position between said feeder members, substantially as described.

4. A blank feeding device, comprising a fixed hopper, two superimposed feeder members rotatably mounted within the hopper and having a plurality of vertical feed channels, means for imparting a step-by-step rotary movement to said members, and a separating or cut-off device interposed between said members, the base of the hopper having a discharge passage located directly below the effective portion of the separating or cut-off device, substantially as described.

5. A blank feeding device, comprising a

- fixed hopper, two superimposed feeder members rotatably mounted within the hopper and having a plurality of vertical feed channels, means for imparting a step-by-step 5 rotary movement to said members, and a separating or cut-off device interposed between said members, the base of the hopper having a discharge passage located directly below the effective portion of the separating 10 or cut-off device, together with an agitator device rotatably mounted in said hopper above the feeding members, substantially as described.
6. A blank feeder comprising a hopper 15 having its lower portion interiorly enlarged, a ratchet ring rotatably seated in said enlarged portion, a pawl mechanism for intermittently engaging and actuating the ratchet ring, and feeder members rotatably 20 mounted within said hopper and ratchet ring and having a plurality of vertical feeding channels arranged to receive and feed the blanks in edgewise positions, substantially as described.
7. A blank feeder comprising a hopper 25 having its lower portion interiorly enlarged, a ratchet ring rotatably seated in said enlarged portion; a pawl mechanism for intermittently engaging and actuating the ratchet 30 ring, and feeder members rotatably mounted within said hopper and ratchet ring and having a plurality of vertical feeding channels arranged to receive and feed the blanks in edgewise positions, together with a blank 35 separating or cut-off device held in fixed position between the feeder members, and the base portion of the hopper member having a discharge passage whose upper end is immediately below the effective portion of 40 the separating or cut-off device, substantially as described.
8. A blank feeder comprising a hopper, a plurality of feeder members rotatably mounted within the hopper, the base of the 45 hopper having a discharge passage, a delivery chute connecting with the discharge passage and a movable gate for said chute, together with means for reciprocating said gate, substantially as described.
9. In a feeder for metal blanks, a hopper 50 having downwardly curved convex inner walls, a feeder member in said hopper rotatable about an axis extending upwardly through said hopper centrally thereof, and means for receiving blanks from said member, substantially as described.
10. In a feeder for metal blanks, a hopper 55 having downwardly curved convex inner walls, a feeder member in said hopper, an agitator for insuring the delivery of blanks 60 to said member, means for rotating said agitator about an axis extending upwardly through said hopper centrally thereof, and means for receiving blanks from said member, substantially as described.
11. In a feeder for metal blanks, a hopper, an agitator therein, a plurality of feeder members rotatably mounted in said hopper below said agitator, and means for receiving blanks as delivered by said members, substantially as described.
12. In a hopper for feeding metal blanks, a plurality of feeder members rotatably mounted therein, each of said members having a blank receiving opening, cut-off means 70 interposed between said members, and means for receiving blanks as delivered by said members, substantially as described.
13. In a feeder for metal blanks, a hopper, a base having a delivery opening, a feeder member in said hopper, said member having a blank receiving pocket, means for rotating said member to bring the pocket in alinement with said opening, and a cut-off above said member preventing the passage of a plurality of blanks through said opening when the pocket is in alinement therewith, substantially as described.
14. In a feeder for metal blanks, a hopper, a base having a delivery opening, a feeder member in said hopper, said member having a blank receiving pocket, means for rotating said member to bring the pocket in alinement with said opening, a cut-off above 80 said member preventing the passage of a plurality of blanks through said opening when the pocket is in alinement therewith, and a second feeder member above said cut-off, substantially as described.
15. In a feeder for metal blanks, a hopper, a base having a delivery opening, a feeder member in said hopper, said member having a blank receiving pocket, means for rotating said member to bring the pocket in alinement with said opening, a cut-off above 90 said member preventing the passage of a plurality of blanks through said opening when the pocket is in alinement therewith, and agitating means insuring the delivery of blanks to said member, substantially as described.

In testimony whereof, I have hereunto set my hand.

JOHN A. McGINNIS

Certificate of Correction.

It is hereby certified that in Letters Patent No. 1,455,639, granted May 15, 1923, upon the application of John A. McGinnis, of Wheeling, West Virginia, for an improvement in "Feeders for Metal Blanks," errors appear in the printed specification requiring correction as follows: Page 1, line 97, after the word "peripheries" insert the word *with*; page 3, line 55, claim 9, after the syllable "mem" insert the syllables *ber, substan*; and that the said Letters Patent should be read with these corrections therein that the same may conform to the record of the case in the Patent Office.

Signed and sealed this 19th day of June, A. D., 1923.

[SEAL.]

WM. A. KINNAN,
Acting Commissioner of Patents.
